UNITED STATES PATENT OFFICE.

JOHN K. HENCKEN, OF BROOKLYN, NEW YORK.

CENTRIFUGAL CASTING MACHINE.

Application filed November 14, 1925. Serial No. 68,970.

This invention relates to centrifugal casting machines, and is herein shown as embodied in a machine particularly adapted to be used in casting ingots and the like from which railway rails, beams, girders, etc., are rolled.

Probably in no other field of manufacture than railway rails is it more important that the finished product be represented in a flawless homogeneous metallic mass of fine grain or texture since railway rails are exposed, when put into use, to a variety of destructive factors, such as bending, shearing, compression, impact, and abrasive forces, as well as stresses and strains resulting from changes in temperature, all of which forces, stresses and strains are represented in most severe forms; and it is not practicable to test the finished product otherwise than fragmentarily to determine the condition of its internal structure, so that defects remain latent and undetected until actual use develops them, at times with disastrous consequences.

According to present day methods of manufacturing railway rails, great difficulty is experienced in obtaining a finished product free from defects resulting from blow-holes, piping, segregations, coarse crystalline structure, and enclosed slag, oxides, and other foreign matter. These defects do not result from the inability to produce steel of the proper composition at the furnace, but arise out of the methods of casting the ingots from which the rails are rolled.

The general object of my invention is to obviate the above defects in the ingot casting process preparatory to rolling, so that rails of a fine grain or texture may be consistently produced, free from blow-holes, piping segregations, coarse crystalline structure and enclosed slag, oxides, and other foreign matter; and my invention is characterized by the provision of a centrifugal mold, comprising a rotary table, carrying a mold into which the molten metal to be cast in the form of ingots or the like is introduced, and in which it is subjected to strong centrifugal action while in liquid condition and during the cooling and solidifying process, in combination with means for skimming off and removing the lighter material which floats to the inner part of the mold and contains the impurities from which the pure metal is separated by centrifugal action during the casting period.

My invention is further characterized by the provision of means for constantly subjecting the molten metal, within the mold, to the action of a flame to prevent oxidation at the surface of the metal during the filling up of the mold with molten metal, whereby ingots or the like are produced which are free from oxides throughout their cross sectional areas; and my invention also includes simultaneous casting and oxidizing-prevention treatment in a plurality of molds.

Certain specific objects of the invention and various advantages of the same will become apparent from the following description when taken in connection with the accompanying drawings, in which—

Figure 1 is a plan view of the machine embodying my invention.

Figure 2 is a vertical central section thereof taken on the line 2—2 of Figure 1.

Figure 3 is a plan view partly in section of a modified mold.

Figure 4 is a central sectional view, showing the mold of Figure 3 positioned within the rotary table and substituted for the mold sections of Figure 1, and showing the modified form of scraper required.

Figure 5 is a plan view of another modified form of mold.

Figure 6 is a central sectional view taken on line 6—6 of Figure 5, and showing fragmentarily in section the table into which the mold is adapted to fit.

With all of the forms of my invention shown herein a rotary table 10 is employed, such table being suitably housed, as is customary, within a pit 11 formed in a suitable masonry or other structure 12 beneath the floor level of a casting room within which the machine embodying my invention may be installed. The table 10 is suitably connected to the flanged portion 13 of a tubular drive shaft 14, provided at its lower end with a beveled gear 15, adapted to mesh with a pinion 16, carried by a drive shaft 17, which is adapted to be connected to a suitable source of power, not shown, for rotating the table 10. The tubular shaft 14 is suitably journaled within a bearing 18 mounted centrally of the pit 11 and anchored to the masonry structure 12. In order to adequately support the table 10, a plurality of roller bearings 19 are provided. These bearings are suitably mounted upon the masonry structure 12 and are so located as to engage an annular bead or bearing sur-

face 20 formed on the underneath side of the table 10, relatively near its periphery.

The table 10 is provided with an upstanding annular flange or wall 21 which is formed on its periphery with a plurality of fins or ribs 22 for the purpose of reinforcing the same against such stresses and strains as are imparted to the wall 21 due to the centrifugal force resulting from rotation of the table. In addition to reinforcing the table, the fins 22 may also serve to conduct away and dissipate, from the table 10 and its upstanding wall 21, heat which is derived from the molten metal during the casting period.

Over the pit 11 and the table 10 is positioned a suitable floor 23 which serves to cover the machine within the pit 11 and thus guard the operators or other foundrymen against hazardous risks incident to centrifugal casting. This floor may be of any suitable material such as heavy sheet metal and is shown as supported on the lower flanges of horizontally disposed I-beams 25 which are arranged over the pit 11 and are adapted to support certain other elements, hereinafter described, entering into the structure of the machine embodying my invention. It may also have additional cross-beams to support it, indicated as 24 in Fig. 1.

The table 10, at its periphery, is provided with an annular groove 26 which forms, with the upstanding flange 21, a pocket 26' adapted for the reception of the several forms of annular molds hereinafter more particularly described, the pocket 26 being lined with a suitable heat-insulating material 27 to prevent undue transfer of heat from the molten metal to the table which may result in too rapid cooling or chilling of the metal during or after casting.

In Figures 1 and 2, I have shown one form of mold 28 which comprises a plurality of mold sections 28' herein shown as four, so shaped that they are adapted, when arranged in an end-to-end relation, to fit into the pocket 26' as shown. Each section is formed with a base portion 29 from which project side walls 30, the side walls being slightly tapered, as shown, to permit the ingots to be readily removed from their respective mold cavities. The mold cavities are separated from each other by end walls 31 which are also slightly tapered to facilitate removal of the ingots. Each of the mold sections is preferably provided with a plurality of lugs 32 which enable the sections to be withdrawn, as by means of suitable tongs and derricks, from the casting table through an opening in the floor 23 provided with a trap door 34 which may be closed during the casting operation.

It will be noted that the end walls 31 do not extend to the inner edges of the side walls 30 but lie wholly within the mold.

These end walls terminate short of the side walls 30 so as to permit a skimming tool 35 to be projected into the mold during the casting operation for the purpose of skimming off the inner surface of the molten metal, whereby slag and other lighter impurities are separated from the pure metal which is thrown, by centrifugal force, to the outer portion of the mold. The skimming tool 35 is suitably mounted within a holder 36 and is retained therein by any suitable means, such as a set screw 37. The holder 36 is preferably formed integral with a trough 38 which comprises a rear curved wall 39 and a base plate 40, the forward edge of which base plate may be beveled or inclined as shown at 41. The skimming tool 35, together with its associated chute, is suspended from a carriage 42 which is mounted to operate upon the I-beams 25 and is adapted to be adjusted thereon, to effect a corresponding radial adjustment of the skimming tool 35, by means of a screw shaft 43, one end of which is journaled to the carriage 42, whereas the other end is provided with a hand-wheel 44 and maintained in screw-threaded engagement with a bracket or yoke 45 secured to the I-beams 25. As the molten metal is removed from the mold 28, it is directed into a vertical chute 46 into which the trough 38 projects. The chute 46 is suitably supported by the I-beams 25 and projects downwardly through the tubular shaft 14 and is adapted to transfer or direct the skimmed off material into a slag car or the like, not shown, which may be arranged beneath the masonry structure 12.

The molten metal is directed into the mold 28 through a nozzle 47 supported upon the I-beams 25. The outlet end 48 of the nozzle is disposed horizontally and is curved in the general direction of rotation, as indicated by the arrow A in Figure 1, so that the flow of molten metal into the mold is facilitated during the operation of the machine.

In order to guard against oxidation of the metal as it is being built up within the mold 28, oxidizing-prevention treatment may be carried on simultaneously with the molding operation, and to enable such treatment to be effected I have provided a pair of arcuate shaped gas burners 49 which are so arranged as to direct their respective flames upon the surface of the metal within the mold. These burners are supported concentrically with respect to the axis of the table by means of brackets 50 and are connected by means of distributor pipes 51 to a common supply pipe 52 which is supported by the nozzle 47. Into the common supply pipe 52, lead a pair of pipes 53 and 54, the former of which may carry air and the other gas, the two fluids being mixed together within the common supply pipe 52 and the former being

utilized to support combustion of the other. If desired, the gas may be shut off by a valve 55 and by leaving open the valve 56, controlling the air supply, air alone may be directed onto the surface of the molten metal to cool the same after the casting operation and prior to removal of the ingots.

In Figure 3, I have shown a modified form of mold 57 which is in the form of an annular ring, provided with a pair of annular mold cavities 58 which are separated by means of an intermediate rib or wall 59. This mold is adapted to be placed within the table 10, shown in Figures 1 and 2, but since its cross-sectional width is somewhat less than that of the mold 28, a filler 60 is employed to fit into the space afforded between the mold and the upstanding flange 21 of the table 10. The filler 60 is in the form of an annular ring which is provided on its inner surface with a coating of heat-insulating material 61 similar to the insulating material with which the pocket 26' is lined. In order to facilitate removal of the castings formed with the type of mold shown in Figures 3 and 4, a block 62 may be provided for each cavity 58. These blocks are removable and are inserted at diagrammatically opposite points so as to maintain balance in weight between opposite halves of the mold. The blocks 62 are formed with inclined faces 63 which, when the castings shrink as they cool, will permit a suitable tool to be introduced into the mold cavities 58 behind the molded rings to facilitate their removal. These rings may be removed by first prying out one end of each, thus enabling the rings to be grasped by a suitable tool and thereafter stripped from the mold and withdrawn through the opening as the table 10 is slowly rotated while they are in a semi-plastic condition.

It will be understood that oxidation of the molten metal when casting with the mold of the type shown in Figures 3 and 4 may be prevented by the action of the flame of the burners 49 as previously described. It will be further understood that the impurities are removed from the metal when employing the type of mold shown in Figures 3 and 4 through the instrumentality of a scraper tool as also previously described. The scraper tool 64 may be somewhat modified, however, as shown in Figure 4 so as to present two cutting edges 65, one for the upper cavity 58 and the other for the lower cavity 58.

In Figures 5 and 6, wherein I have shown still another modified form of mold 66, a helical cavity 67 is provided in such mold. One convolution of the cavity is separated from the adjacent convolution by means of a helical wall 68. This helical wall, it will be noted, is of a width somewhat less than the side walls 69 of the mold so as to

permit the use of the straight edge cutting tool 35 shown in Figure 1. The modified form of mold 66 is adapted to be retained within the pocket 26' of the table 10 by the same ring 60 that is employed to retain the mold 57 properly positioned.

In order to facilitate removal of the cast metal, when the modified form of mold 66 is employed, the upper convolution of the cavity 67 may terminate with an inclined bottom wall 70 which, when the cast metal contracts or shrinks as it cools, will permit a suitable tool to be introduced into the cavity at the rear of the casting. By means of such a tool one end of the casting, while in a plastic or semi-plastic state, may be withdrawn, thus enabling it to be grasped by a suitable tool so that it may be stripped from the spiral cavity 67 through the opening 33 as the table is slowly rotated.

From the foregoing, it will be apparent that separation of the pure and uncontaminated metal from the impure metal may be effected in the same general manner. That is to say as the metal is introduced into the molds from the nozzle 48 it, by centrifugal action, is thrown outwardly away from the center of rotation and as the metal builds up within the molds, the purer and denser metal which is heavier than the impure and less dense metal displaces the impure and less dense metal which is forced, due to such displacement, towards the center of rotation. As the molds become filled with metal the scraping-off tool removes the surface metal and directs it into the chute 46. As soon as the rejected or cast-off metal is observed as entering the chute, it becomes known that the molds are full and pouring of the metal may then be discontinued. However, no exact period throughout which pouring of the metal should continue can be stated, inasmuch as varying factors, such as speed of rotation, the kind and quality of metal employed, and degrees of purity and character of texture required in the finished product, may determine this.

The type of mold shown in Figures 1 and 2 for casting ingots may be employed when conditions are such as to require many passes through the rolling mill to produce the finished article, and molds of the types shown in Figures 3 to 6 inclusive, may be employed when it is desired to cast the molten metal to more nearly its finished shape and dimensions, in which case fewer passes through the rolling mill may be required. Regardless of the type of mold employed much time, labor and expense may be saved at the rolling mill, by subjecting the ingots or the like to fewer passes to produce the finished article, since a great number of passes, as heretofore required, are not necessary to reduce the material to a fine grain or texture for the reason that castings produced in ac-

cordance with this invention are of a fine grain or texture due to the absence of the coarse crystalline structure and the absence of the impurities which have been separated 5 from the pure metal during the casting period.

Having described certain embodiments of my invention what is claimed is:

1. A centrifugal casting machine comprising 10 a centrifugal mold, means for introducing molten metal into the mold, means for subjecting the introduced metal to centrifugal action within the mold whereby the relatively heavy metal is forced towards the 15 periphery of the mold and the lighter material is moved toward the axis of rotation, skimming means projecting into the mold for removing said lighter material from the mold, and means for receiving the lighter 20 material so removed and for directing it out of the vicinity of the mold.

2. A centrifugal casting machine comprising 25 a rotary table, a mold carried by said table, means for introducing molten metal into the mold, means for rotating said table and said mold whereby the introduced metal is subjected to centrifugal action to force 30 the relatively heavy metal towards the periphery of the mold and to move the lighter material towards the axis of rotation, a skimmer projecting into said mold for removing the lighter material from the mold, and means cooperating with said skimmer 35 for directing the removed material out of the vicinity of said table.

3. A casting machine comprising a rotary 40 table having an annular pocket formed therein, an annular mold carried within said pocket and having mold cavities of a depth less than that of the mold, means for introducing molten metal in the mold, means for rotating said table whereby the introduced metal is subjected to centrifugal action to

force the relatively heavy metal towards the periphery of the mold and to move the lighter material towards the axis of rotation, a skimming tool projecting into said mold for removing the lighter material from the mold, and means for receiving the lighter material so removed and for directing it out of the vicinity of the mold.

4. A casting machine comprising a rotary 45 table having an annular pocket formed therein, an annular mold removably carried within said pocket and having mold cavities of a depth less than that of the mold, means for introducing molten metal in the mold, means for rotating said table whereby the introduced metal is subjected to centrifugal action to force the relatively heavy metal towards the periphery of the mold and to move the lighter material towards the axis of rotation, a skimming tool projecting into said mold for removing the lighter material from the mold, means for receiving the lighter 55 material so removed and for directing it out of the vicinity of the mold, and means for varying the position of the skimming tool with respect to the depth of the mold.

5. A casting machine comprising a rotary 60 table, an annular mold carried by said table, means for introducing molten metal into said mold, means for rotating said table whereby the introduced metal is subjected to centrifugal action to force the relatively heavy metal towards the periphery of the mold and to move the lighter material towards the axis of rotation, the latter named means comprising a tubular shaft, means for removing the lighter material from said mold during rotation, and means for directing the removed material through said shaft to a point remote from said table.

In testimony whereof, I have affixed my signature to this specification.

JOHN K. HENCKEN.
